Kenneth J. Germeshausen, Cambridge, Mass.

Application July 30, 1941, Serial No. 404,724

9 Claims. (Cl. 179—100.4)

This application relates to a reproducer, and more particularly to an improved reproducer and associated circuits for electrically reproducing recorded mechanical variations.

One feature of this invention is that it provides improved record reproducing apparatus; another feature of this invention is that it provides a strain sensitive coated vibrator-translator and associated circuits developing greater voltage variations for a given mechanical movement; another feature of this invention is that it almost completely balances out undesired harmonic distortion; yet another feature of this invention is that it enables the vibrator-translator coating resistance included between the poles of the source of voltage to be much higher than heretofore; a still further feature of this invention is that it enables push-pull operation without a coupling transformer; other features and advantages of this invention will be apparent from the following specification and the drawings, in which:

Figure 1 is a circuit diagram of reproducing apparatus embodying my invention; Figure 2 is a side elevational view of a vibrator-translator element adapted to be used in the circuit of Figure 1; Figure 3 is a top plan view of the element shown in Figure 2; Figure 4 is a side elevational view, from the other side, of the element shown in Figure 2; Figure 5 is a front elevational view, with the damper removed, of the same element; Figure 6 is a circuit diagram of a modification of my invention; Figure 7 is a side elevational view of a vibrator-translator element adapted to be used in the circuit shown in Figure 6; Figure 8 is a side elevational view of the other side of the element shown in Figure 7; and Figure 9 is a skeleton view of the coatings and rivets in the same element, to more clearly show the arrangement and connection of these parts.

I have found that a considerable improvement in record reproduction is obtained by the use of a vibrator-translator of insulating material of a low modulus of elasticity, as Celluloid or polystyrene, with a coating or layer on at least one surface of material having high resistance and sensitive to strain, as a sprayed-on coating of finely divided graphite. Such an element is adapted to have one end rigidly mounted in a tone arm and the other end vibrated by the engagement of a needle rigidly mounted therein with the record being reproduced, vibration of the element causing variation in the strain in the coating and thus variation in its resistance. By developing a voltage across the length of the resistance coat-

ing variation of its impedance varies the voltage drop, this voltage variation faithfully following the mechanical variations in the record and being adapted to be supplied to the grid of the first tube of an amplifier, to be highly amplified and supplied to a speaker. Such reproducing apparatus has been more fully described in my co-pending application, Serial No. 340,156, filed June 12, 1940, and the general advantages and basic principles of such reproducing apparatus will not be further described here except as they may be necessary to enable clear understanding of the present improvements. This application is a continuation-in-part of my aforesaid earlier application.

Inasmuch as the basic ideas and features of such reproducing apparatus have been claimed in my abovementioned earlier application, the present application is more particularly directed to specific forms of vibrator-translator elements, and associated circuits, which provide greater voltage variation for a given mechanical movement, and have other attendant advantages. Merely as a suggestive term, and without intending to impose any limitations thereby, the present application may be considered as directed to push-pull operation. That is, layers on opposite sides of the vibrator-translator element have their impedance varied simultaneously but oppositely by vibration of the element, these layers being serially connected to provide a connection at their inner or mutually connected ends and at their outer or other ends. While these three connections may be arranged in conventional push-pull fashion by connecting the energizing voltage to the center connection and to the center tap of a transformer and the outer ends of the layers to the outer ends of the transformer winding, I have found other circuit arrangements to be more advantageous. In any case, however, this "push-pull" arrangement provides increased voltage variation for a given mechanical movement, balances out second harmonic distortion, and has other advantages.

Turning now more particularly to the embodiment of my invention illustrated in Figures 1 to 5, the variable resistance symbols indicated as 10 and 11 represent strain sensitive coatings on opposite sides of the vibrator-translator element. It will be noted that these have what I am terming for convenience their inner ends connected by the lead 12, so that the resistances 10 and 11 are in series. The other end of the resistance 10 is connected by the lead 13 to the B+ supply source, also connected to the plate 14 of ampli-

ing tube 15 through the resistor 16. In accordance with conventional practice the screen grid 17 of the tube is connected to the B+ source through a voltage reducing resistor 18; the other or negative end of the plate voltage supply is connected at some point to the bus wire 19; and the cathode 20 of the tube is connected through a biasing resistor 21 to the bus wire 19, and directly connected to the suppressor grid 22.

The other end of the resistance coating 11 is also connected to the negative bus wire 19, it being understood that this is grounded in accordance with conventional practice. The center connection 12 between the two resistances 10 and 11 is connected through the coupling condenser 23, a correction network comprising the condenser 31 and a high value variable resistor 32 in shunt therewith, and the lead 24 to the control grid 25 of the tube 15, a load resistor 26 being connected in shunt between this grid and ground. Each portion of the vibrator-translator resistance (that is, each of the resistances here separately identified as 10 and 11) is preferably of a quarter megohm to a megohm resistance. The circuit arrangement shown in Figure 1 is particularly advantageous in that it provides a relatively high value bleeder resistor across the energizing voltage (both of the resistance portions in series), and a relatively low (only one portion) grid to ground resistance, tending to minimize oscillation and pick-up difficulties. The output of the tube 15, as may be seen, is developed between the terminals 27 and 28 across the load resistor 29, the plate lead having in series therein the coupling condenser 30. A correction network may be included in the output circuit rather than the input circuit if desired.

One particular circuit which I have tested employed the following values for the circuit elements: the two portions 10 and 11 had a resistance of one-quarter megohm; the condenser 23 had a value of .05 mf.; the resistor 26 had a value of one-half megohm; the biasing resistor 21 had a value of 500 ohms; the plate resistor 16 was 100,000 ohms; the condenser 30 was .05 mf., and the condenser 31 was .0005 mf.; the variable resistor 32 had a maximum value of 4 megohms; the output resistor 29 had a value of one-quarter of a megohm; the screen grid resistor 18 had a value of 350,000 ohms, the condenser 33 shunting it to ground having a value of .1 mf. The tube which I used was a 6SJ7, the plate supply voltage being 300 volts.

Turning now more particularly to Figures 2 to 5, a vibrator-translator element adapted to provide the desired variable resistors is shown. It comprises as the base or principal portion thereof a Celluloid or similar element having a beam-like forward portion 35 adapted to be vibrated by engagement of a very short needle 36, rigidly mounted in its outer end, with a rotating record, and a rear enlarged portion 37. This latter portion is adapted to be clamped, bolted or otherwise rigidly mounted in a tone arm, either directly or through some intermediate means, as a cartridge. A long thin damper 38 of very soft material is provided near the outer end to give the vibrating beam-like portion the desired vibrational characteristics. After the base of Celluloid or other material has been cut to the proper form I mask it appropriately and then spray on a coating of finely divided graphite or the like in the shapes shown, this coating making connection with rivets or other connectors at suitable points and being subsequently covered with lacquer or some

other protective medium. Referring to the particular arrangement shown here, one coating extends from the rivet 39 down to the bottom edge of the side of the element shown in Figure 2, and then forwardly along this edge, this portion being identified as 40; the coating then has a vertical portion out near the end of the needle, identified as 41, running up to the upper edge of this side, then running back along this side in the portion identified as 42 to connect with the rivet 43. The coating then extends across the forward face of the rear enlarged portion, as may be best seen in Figure 5, this portion of the coating being identified as 44. In order to avoid a high resistance path on the inactive base portion of the needle these portions of the coatings may be covered with silver paint or metal foil.

Now turning to Figure 4, showing the other side of the needle, it will be seen that the coating 20 extends forwardly along the top edge of this side of the needle, this portion being identified as 45, downwardly near the outer end of the needle in a portion identified as 46, and back along the bottom edge of the needle in a portion identified as 47 to make connection with the rivet 48. By this arrangement the coating portions 40 and 42 provide the resistance schematically identified as 10 in Figure 1, the coating portions 45 and 46 providing the resistance schematically identified as 11 in Figure 1, the arrangement being such that lateral vibratory movement of the element (as a result of movement of the needle in the grooves of a laterally cut record) causes simultaneous but opposite variation of the resistances 35 on the opposite sides of the translating element. The cross-over portion 44 provides the center connection between the resistance portions on opposite sides of the needle, corresponding to the leads schematically illustrated as 12 in Figure 1, 40 the connection to the grid 25 being conveniently taken off from the rivet 43. The connections schematically illustrated as 13 and 19 in Figure 1 may be conveniently taken off from the other ends of the resistance coatings by connections to 45 the rivets 39 and 48. It will be understood that the advantages of my push-pull circuit illustrated in Figure 1 can be achieved by a vibrator-translator element having a coating going out one side, crossing over at the end, and coming back on the 50 other side, as illustrated in my above-mentioned application. Such an arrangement, however, requires a flexible wire connection to the outer end of the needle; whereas by having the resistance coating follow a U-shaped path out to the end and back to the base of each side of the translator element, as here shown, all connections may be made at the fixedly mounted rear or base end of the element.

Turning now more particularly to the circuit 60 shown in Figure 6, it will be seen that four variable resistance portions 50, 51, 52 and 53 are provided on the vibrator-translator element, as will hereafter be more fully described. These are so arranged that they are connected in a diamond, 65 and so that lateral vibration of the translator element causes simultaneous variation of all four resistors, the variation of any two adjacently connected resistances being in opposite directions, the arrows on the circuit diagram being oppositely pointed to indicate this. Current from the negative terminal of the B voltage supply, here indicated as the battery 54, is supplied through the lead 55 to one corner of the resistance diamond, the other corner being connected through the lead 70 56 to the positive side of this source. The other

two corners of the resistance diamond are connected to tubes arranged in push-pull relation, the upper corner (speaking with respect to Figure 6) being connected through the lead 57 and the coupling condenser 58 to the grid 59 of the tube 60; and the bottom corner being connected through the lead 61 of the tube 64. While these tubes are shown as simple triodes for convenience of illustration, it will be understood that in practice they would be pentodes or other multi-element tubes. In accordance with conventional practice the cathode elements 65 and 66 are connected through biasing resistors 67 and 68 to the grounded negative terminal of the B supply; and the plates 69 and 70 are connected to the outer ends of the primary 71 of a push-pull transformer, the positive side of the plate supply voltage being connected to the center tap of this primary. The secondary 72 of this same transformer is connected to the succeeding tube 73 of a single ended amplifier, one end of the secondary being connected to the grid 74 and the other end to the cathode 75 through the biasing resistor 76. As before, input load resistors 77 and 78 are employed in shunt between the grid and cathodes of each of the tubes 60 and 64, these preferably having a resistance slightly higher than the resistance of any particular section or portion of the resistance diamond provided by the coatings or strain sensitive layers on the vibrator-translator element. The values of the various circuit constants would be approximately similar to those previously described.

Turning now more particularly to Figures 7 to 9 a form of vibrator-translator adapted to be used in the circuit shown in Figure 6 is illustrated. In this particular form the base or enlarged rear portion 80 of the element is provided with only two rivets 81 and 82. The coating may be considered as starting at the rivet 81 and running along the top edge of one side of the forward or beam-like portion of the element, as shown in Figure 7, this portion being identified as 83, then across at the end of the element in the portion identified as 84, better seen in Figure 9, and back on the other side of the element shown in Figure 8, this portion being identified as 85, and extending clear along the upper edge of the base portion to make connection with the rivet 82. Referring back to Figure 7, it will be seen that another layer or coating of the high resistance material starts at the rivet 82, extends down to the bottom edge of this side of the element, and along this bottom edge to the front of the element, this portion being identified as 86; then it crosses over the front end of the element in the portion identified as 87, better seen in Figure 9, and runs back along the bottom edge of the side shown in Figure 8, as the portion identified as 88, to make connection with the other side of the rivet 81.

The two terminals provided by the rivets 81 and 82 may, for example, be used as the corners of the resistance diamond connected to the voltage supply; whereas the grid connections may be provided by pigtailed or flexible wires 89 and 90 at the outer end of the needle. As compared with a simple vibrator-translator having a resistance coating on only one side, the push-pull arrangement first described provides double the voltage variation for a given translator element flexure, and the arrangement last described above provides four times the voltage variation for the same movement of the end of the element. Without the push-pull arrangement it has been neces-

sary, in some cases, to use a preamplifier because of the small voltage variation; but with either of the above described push-pull arrangements sufficient voltage variation can be secured to dispense with the necessity of a preamplifier.

Push-pull arrangement of the strain sensitive coatings is also highly desirable in that it balances out sensitivity variations arising from what may be termed initial or average compression of the coating. The sensitivity per unit deflection is decreased where the coating was under compression before its flexure strain, and increases where it was stretched. Resistance pick-ups using only a single coating have showed variations in response to a single continued tone where the deflection did not start from zero position, as where the coating is initially compressed or expanded because of tone arm lag or an off-center record, this objection being completely eliminated by the push-pull arrangement.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. Reproducing apparatus of the character described, including: a tone arm; a single beam-like vibrator-translator element of insulating material rigidly mounted in the tone arm at one end and having on opposite sides thereof and connected at one end coatings of material having its resistance varied by strain, whereby the resistance of the coatings is simultaneously but oppositely varied by vibratory movement of the element; a stylus directly connected to the other end of the element for vibrating it in accordance with mechanical variations in the record being reproduced; and a circuit connected to the junction and outer ends of the coatings and adapted to develop voltage variations as a result of said resistance variations, the effect of the resistance variations in said coatings being additive for the desired vibrations.

2. Vibration-translating apparatus of the character described, including: a translating element having two serially connected portions adapted to have their impedance simultaneously but oppositely varied in accordance with variations in the record being reproduced; an amplifying tube including grid and cathode elements; a source of voltage connected across the outer ends of said portions; and connections from the central connection between said portions to one of the tube elements and from an outer end to the other tube element, said connections having low impedance at high frequencies.

3. Vibration-translating apparatus of the character described, including: a translating element having two serially connected portions of high resistance adapted to have their resistance simultaneously but oppositely varied in accordance with the vibrations being translated; an amplifying tube including grid and cathode elements; a source of voltage connected across the outer ends of said portions; and connections from the central connection between said portions to one of the tube elements and from an outer end to the other tube element, said connections having low impedance at high frequencies.

4. Reproducing apparatus of the character described, including: a tone arm; a beam-like vibrator-translator element rigidly mounted in

the tone arm at one end and having on opposite sides thereof and connected at one end coatings of high resistance material having its resistance varied by strain, whereby the resistance of the coatings is simultaneously but oppositely varied by vibratory movement of the element; means connected to the other end of the element for vibrating it in accordance with mechanical variations in the record being reproduced; an amplifying tube including grid and cathode elements; a source of voltage connected across the outer ends of said portions; and direct connections from the central connection between said portions to one of the tube elements and from an outer end to the other tube element.

5. Vibration-translating apparatus of the character described, including: a translating element having four portions connected in a diamond, these portions being adapted to have their respective impedances varied simultaneously in accordance with the vibrations being translated, the arrangement being such that any two adjacent impedances vary oppositely; a source of voltage connected to two of the corners of the diamond; and a circuit connected to the other two corners of the diamond and adapted to have voltage variations developed therein.

6. Apparatus of the character claimed in claim 5, wherein said portions are layers, on a vibra-

tory element, of material having its impedance varied by strain.

7. Apparatus of the character claimed in claim 5, wherein the translating element is a beam-like member having two independent coatings, on each of two opposite surfaces, of high resistance material having its resistance varied by strain.

8. A vibration-translating element comprising a beam-like member of insulating material having a low coefficient of elasticity, the member having on each of two opposite surfaces thereof a coating of high resistance material having its resistance varied by strain, this coating extending from one end of the beam-like element to the other and back again on each side thereof, whereby all of the terminal connections are made at one end of said element.

9. A vibration-translating element comprising a beam-like member of insulating material having a low coefficient of elasticity, the member having on each of two opposite surfaces thereof separate coatings of high resistance material having its resistance varied by strain, each of these separate coatings on each side connecting at both ends to the ends of a coating on the other side of the element, whereby four resistance portions are provided, the connections between the ends of these portions being in the form of a diamond.

KENNETH J. GERMESHAUSEN.
